UNITED STATES PATENT OFFICE

KARL MAIER, OF STUTTGART, GERMANY, ASSIGNOR TO UNION SPECIAL MASCHINEN-FABRIK, G. M. B. H., OF STUTTGART, GERMANY

RUFFLING MECHANISM FOR SEWING MACHINES

Application filed March 18, 1929, Serial No. 347,920, and in Germany April 2, 1928.

The invention relates to new and useful improvements in ruffling mechanisms for sewing machines.

In the patent granted James R. Moffatt, January 2, 1917, No. 1,210,671, there is shown a ruffling mechanism which can be moved laterally of the line of feed to an inoperative position and when thus positioned the ruffling blade is disconnected from the actuating mechanism therefor. The operator through a treadle controlled mechanism may move the ruffling mechanism laterally so as to bring the ruffling blade into the line of feed and at the same time connect said ruffling blade to the actuating mechanism therefor. A latch is provided for holding the ruffling mechanism in its actuating position, but this latch is controlled by a treadle which is lifted by a spring, and when the treadle is released the latch is released and the ruffling mechanism moved to inoperative position.

The present invention has to do with a ruffling mechanism of the above type, and an object of the invention is to provide a manually controlled means for holding the ruffling mechanism in normal actuating position so that the treadle by which it is shifted may be released.

A further object of the invention is to provide a ruffling mechanism of the above character which is automatically thrown to inoperative position when the manually controlled latching means is entirely released.

A further object of the invention is to provide a ruffling mechanism of the above character wherein the manually controlled latching means may be operated to throw the ruffling blade to an ineffective actuating position without moving the ruffling blade laterally to inoperative position.

These and other objects will in part be obvious and will in part be hereinafter more fully disclosed.

In the drawings which show by way of illustration one embodiment of the invention:—

Fig. 1 is a view partly in section and partly in plan showing the ruffling mechanism and the position of the same on the sewing machine.

Fig. 2 is a front view of the same.

Fig. 3 is a detail showing partly in section and partly on front elevation the actuating mechanism for the ruffling blade.

Fig. 4 is a view showing the parts as viewed from the end of the carriage.

Fig. 5 is a detail showing the work support, the ruffling blade and the stripper blade.

Fig. 6 is a view showing diagrammatically a fabric ruffled and stitched on the machine.

Fig. 7 is a vertical sectional view at one side of the manually controlled latching device, showing the ruffling mechanism in inoperative position.

Fig. 8 is a similar view but showing the ruffling mechanism in operative position.

Fig. 9 is a view similar to Fig. 8, but showing the ruffling blade in ineffective actuated position.

The invention is directed to a latch controlled mechanism for a ruffling mechanism such as shown in the Moffatt patent referred to above. In this Moffatt patent the ruffling blade is shown as mounted on a carriage which is moved endwise so as to position the ruffling blade either in the line of feed or at one side of the line of feed.

The ruffling blade is carried by an arm mounted on the carriage which is oscillated by a device which becomes connected to the ruffling blade for actuating the same when said blade is moved laterally into the line of feed. The ruffling blade is disconnected from the actuating device when moved laterally to one side of the line of feed. The carriage carrying the ruffling blade is shifted by means of a treadle and the treadle is so connected to the carriage that when depressed the carriage will be moved to position the ruffling blade in the line of feed, connecting the same to its actuating mechanism so that it is automatically thrown into action when the treadle is depressed. When the treadle is released a spring operates to move the carriage so as to place the ruffling blade at one side of the line of feed and automatically disconnect it from its actuating means.

The present invention has particularly to do with a latch controlling device which consists of a lever pivoted to the bracket sup-

porting the carriage on which the ruffling mechanism is mounted. This lever is spring pressed toward the carriage and carries a lug which when the ruffling mechanism is in inoperative position bears against the carriage. When this carriage is moved so as to position the ruffling mechanism in the line of feed, then the lug is moved past the end of the carriage and into such a position that when the treadle is released the spring cannot return the carriage, and thus render the ruffling mechanism inoperative. The operator who depressed the treadle to place the ruffling mechanism in operation may then release the treadle and the ruffling mechanism will continue its operation. The latch controlling device is released by the hand of the operator by pressing against the lower end of the lever. The lug on the lever is of sufficient length so that the operator may move the lever through considerable distance before the lug releases the carriage. The ruffling blade is held in engagement with the material by a spring bearing on an arm which is associated with this latch controlling device. The latch controlling device has an extension which engages the arm when the ruffling blade is positioned in the line of feed and thus holds the ruffling blade in operative position, although the treadle utilized for throwing the ruffling blade into operative position, is released. When this latch controlling device is moved for a slight distance the arm is released and the blade is lifted from the material although it continues to actuate, that is, move back and forth. Through the latch controlling device the operator may, therefore, cause the ruffling blade to become ineffective although it is operated. This partial release of the latch rendering the ruffling blade ineffective is accomplished without withdrawing the ruffling blade from a position containing the line of feed. By depressing the treadle the operator through the control parts thereby can throw the ruffling blade again into engagement with the fabric for operation thereon and the latch will move forward through the action of the spring 38 holding the blade in operative position. Thus it is that groups of ruffles may be made without moving the ruffling blade laterally to an inoperative position. It continues its movements but is rendered ineffective by raising it from engagement with the material.

Referring more in detail to the drawings, the invention is shown as applied to a sewing machine including a supporting bed 1 provided with the usual standard. Mounted on the bed of the machine is a bracket 2 carrying bearing lugs 3 in which a sleeve 4 is mounted for endwise movement. Located in this sleeve is a shaft 4a which is the actuating shaft for the ruffling blade. A carriage 5 is mounted on the sleeve, and this carriage has a forked

portion straddling the upper end 6 of the bracket 2. This forms a support for the carriage which permits the same to be moved endwise, but prevents the same from oscillating. The needle of the machine is indicated at 7 and the feed of the machine is in the direction of the arrow *a* indicated in Fig. 1. Mounted for oscillation on the carriage 5 is a shaft 8. At one end of this shaft is mounted a support carrying a pivoted arm 20, which in turn supports a ruffling blade 12. On the opposite end of the shaft 8 is an arm 9. A spring 10 bears against the under face of this arm 9 and an abutment on the carriage and normally turns the shaft 8 to a limited extent in a clockwise direction.

Mounted on the shaft 8 on the other end of the arm 9 is a roller 11. This roller serves the double purpose of moving the carriage laterally of the line of feed for positioning the ruffling blade 12 for action and also for oscillating the shaft 8 so as to hold the ruffling blade out of operative engagement with the fabric during its lateral movement. The structure referred to is shown and described more in detail in the Moffatt patent, and further reference thereto is not thought necessary.

The ruffling blade 12 is moved into operative position by means of a treadle controlled mechanism which includes a shaft 13 carrying an arm 14 to which the treadle may be connected. The shaft also carries an arm 15 which engages the lower end 16 of a control lever pivoted at 17. The upper portion of the lever 18 carries a cam portion 19 which is adapted to make contact with the roller 11. A spring 18a normally moves the lever 18 in a clockwise direction, as viewed in Fig. 2, and when the treadle is depressed this lever 18 will be moved to the left or in a counter-clockwise direction about the pivotal center 17. When the treadle is depressed and the lever 18 moved to the left at its upper end the cam 19 engaging the roller 11 moves the carriage endwise and positions the ruffling blade in contact with the material. Simultaneous with this endwise movement of the carriage the actuating mechanism for the ruffling blade is automatically connected thereto. This actuating mechanism includes an eccentric 23 on the main shaft (see Fig. 1). Co-operating with the eccentric is an eccentric strap 24 which is connected to an arm 25 carried by a rock shaft 26. This rock shaft 26 carries an arm 27 connected by a link 28 to a bracket 29 mounted on a rod 30. This rod 30 is mounted in suitable bearings so that during the operation of the machine the rod 125 will have a continuous up and down vertical movement. At the upper end of the rod 30 there is a funnel shaped head 31. On the end of the shaft 4a is an arm 33. This arm 33 carries a lug 32 (see Figs. 3 and 4).

When the carriage is moved in an endwise direction so as to position the ruffling blade in the line of feed this lug 32 is moved into the funnel shaped head so as to be engaged 5 by the wall thereof and thus it is that the reciprocations of the rod 30 will cause the shaft 4a to oscillate and this in turn will impart back and forth movements to the ruffling blade. When the carriage is moved so as to 10 position the ruffling blade at one side of the line of feed, then the lug is withdrawn from the funnel shaped head and disconnected therefrom. Associated with the ruffling blade is a stripper 21 carried by a suitable 15 bracket arm mounted on the carriage. When the treadle is depressed the lever 18 is swung to the left, as noted, moving the carriage so as to position the ruffling blade in the line of feed for action and also so as to position the 20 ruffling blade on the material.

When the arm 18 is moved in the opposite direction thru a suitable connection with the carriage it will move said carriage so as to position the ruffling blade at one side of the 25 line of feed. These parts are also shown and described in the Moffatt patent and it is not thought necessary to describe the same more in detail.

The invention is directed particularly to 30 the control device which is manually operated and which performs the double function of holding the ruffling blade in its normal operative position so that the treadle may be released and of releasing the ruffling blade 35 partially so that it may be lifted from the material and thus rendered ineffective without permitting its movement laterally to inoperative position. This control device includes a lever 36 pivotally supported at 37 on the 40 bracket 2. A spring 38 disposed between the lower end of the lever and the bracket 2 normally turns the lever in a clockwise direction as viewed in Figs. 7 to 9. The lever 36 carries a lug 39. This lever is so positioned that 45 when the carriage is in retracted position and the ruffling blade at one side of the line of feed, the lug 39 bears against the carriage as shown in Fig. 7. When, however, the carriage is moved so as to position the ruffling 50 blade in the line of feed then this lug 39 will pass across the end of the carriage and will restrain the carriage from any retracting movement due to the action of the spring 18a when the treadle is released. The lever 36 carries 55 an extension 40. When the lever 36 moves into position to lock the carriage with the ruffling blade in operative position, the extension 40 engages the arm 9 and will hold said arm depressed, although the treadle is 60 released and the lever 18 returns to its normal position. It will be noted that the latching lever is only released so that it can move into engagement with the arm 9 when the carriage is moved to the extreme limit and the ruffling 65 blade is over the line of feed. As a result,

the ruffling blade will be held raised by the spring while the carriage is moving laterally and will only be depressed by the treadle when the ruffling blade is over the line of feed. This affords a means for holding the ruffling 70 blade above the fabric when moved laterally across the edge of the fabric so as to position it in the line of feed. After it is thus positioned, it will be moved into engagement with the fabric and held in operative engagement 75 with the fabric by the extension 40. The lug 39 is of considerable length and therefore the lower end of the lever 36 may be moved inwardly to quite an extent without retracting the lug 39 from the path of movement of the 80 carriage 5. In Fig. 9 of the drawings the latch is shown as depressed at its lower end a sufficient distance so that the extension 40 releases the arm 9, while the lug 39 still engages the carriage 5. When this arm 9 is released 85 the spring lifts the ruffling blade from the material and it will continue to reciprocate in this ineffective position. A group of ruffles may be made, then the lever 36 operated to release the arm 9 and the ruffling blade will 90 cease ruffling although it remains over the line of feed. By depressing the treadle, the lever 18 may be utilized to swing the arm 9 downward, compressing the spring and moving the ruffling blade into contact with the material 95 so as to commence another group of ruffles. When this lever 36 is further depressed, the ruffling blade is not only raised but the lug 39 will be released from the carriage 5 and it will move the ruffling blade to inoperative position. 100

As shown in Fig. 6 the fabric is indicated at 34 and groups of ruffles are indicated at 35.

The operator may at any time, by depressing the treadle, move the ruffling blade into 105 operative position and the lug 39 will move off from the end of the carriage, thus moving into position to restrain the carriage from endwise movement and at the same time depressing the arm 9 and positioning the blade 110 in contact with the material. All of this control of the ruffling blade may be accomplished without stopping the stitching mechanism.

It is obvious that minor changes in the details of construction and the arrangement of the parts may be made without departing from the spirit of the invention as set forth in the appended claims.

Having fully described my invention, what I claim as new and desire to secure by Letters Patent, is:—

1. In a sewing machine a ruffling mechanism including a ruffling blade, means for actuating said ruffling blade, manually controlled means for shifting the ruffling blade into and out of a vertical plane containing the line of feed, yielding means for normally holding said ruffling blade out of engagement with the material, and means operating automatically to move the ruffling blade into en- 125

gagement with the material for operation thereon when said blade has been shifted into a vertical plane containing the line of feed.

- 5 2. In a sewing machine a ruffling mechanism including a ruffling blade, means for actuating said ruffling blade, treadle control means for moving the ruffling mechanism from inoperative to operative position, a 10 spring for moving the ruffling mechanism into inoperative position, a manually controlled latch for holding the ruffling mechanism in operative position when the treadle control means is released, a spring for normally holding the ruffling blade raised from the material when released from said latch.
- 15 3. In a sewing machine a ruffling mechanism including a ruffling blade, treadle controlled means for moving the ruffling mechanism from inoperative to operative position, a spring for moving the ruffling mechanism from operative to inoperative position, and a manually controlled spring pressed latch 20 operating automatically to secure the ruffling mechanism in operative position.

- 25 4. In a sewing machine a ruffling mechanism including a ruffling blade, a spring means for normally holding said blade raised from the material, treadle controlled means 30 for moving the ruffling mechanism from inoperative to operative position, and a manually controlled latch for locking the ruffling mechanism in operative position and for holding the ruffling blade in engagement with the material.

- 35 5. In a sewing machine a ruffling mechanism including a ruffling blade, a spring means for normally holding said blade raised from the material, treadle controlled means 40 for moving the ruffling mechanism from inoperative to operative position, and a manually controlled latch for locking the ruffling mechanism in operative position and for holding the ruffling blade in engagement with the material, said latch being capable 45 of movement for rendering the ruffling blade ineffective without releasing the ruffling mechanism.

- 50 6. In a sewing machine a ruffling mechanism including a ruffling blade, a spring means for normally holding said blade raised from the material, treadle controlled means 55 for moving the ruffling mechanism from inoperative to operative position, a manually controlled latch having a locking lug for holding the ruffling mechanism in operative position and an extension for holding the ruffling blade in contact with the material when said latch moves to lock the ruffling mechanism.

- 60 7. In a sewing machine a ruffling mechanism including a ruffling blade, a spring means for normally holding said blade raised from the material, treadle controlled means 65 for moving the ruffling mechanism from in-

operative to operative position, a manually controlled latch having a locking lug for holding the ruffling mechanism in operative position and an extension for holding the ruffling blade in contact with the material 70 when said latch moves to lock the ruffling mechanism, said lug being of sufficient length so that the latch may be moved to release and render the ruffling blade ineffective without releasing the ruffling mechanism. 75

8. In a sewing machine a ruffling mechanism including a carriage, a ruffling blade mounted on said carriage, a spring means for normally holding the ruffling blade raised from the material, treadle controlled means for moving the carriage in a direction for positioning the ruffling blade for operation in the line of feed, a spring for moving the carriage in the opposite direction, a latch lever, a lug carried by said latch lever, a spring for moving said lug toward said carriage, said lever being disposed so that the lug bears on the face of the carriage until said ruffling blade is moved to operative position when said lug moves off from the carriage and restrains the carriage from endwise movement under the action of the spring so that the treadle may be released. 85

9. In a sewing machine a ruffling mechanism including a carriage, a ruffling blade mounted on said carriage, a spring means for normally holding the ruffling blade raised from the material, treadle controlled means for moving the carriage in a direction for positioning the ruffling blade for operation in the line of feed, a spring for moving the carriage in the opposite direction, a latch lever, a lug carried by said latch lever, a spring for moving said lug toward said carriage, said lever being disposed so that the lug bears on the face of the carriage until said ruffling blade is moved to operative position when said lug moves off from the carriage and restrains the carriage from endwise movement under the action of the spring so that the treadle may be released, said latch lever having an extension adapted to hold the ruffling blade in engagement with the material when said lug passes off from the face of the carriage. 100

10. In a sewing machine a ruffling mechanism including a carriage, a ruffling blade mounted on said carriage, a spring means for normally holding the ruffling blade raised from the material, treadle controlled means for moving the carriage in a direction for positioning the ruffling blade for operation in the line of feed, a spring for moving the carriage in the opposite direction, a latch lever, a lug carried by said latch lever, a spring for moving said lug toward said carriage, said lever being disposed so that the lug bears on the face of the carriage until said ruffling blade is moved to operative position when said lug moves off from the carriage. 105

carriage and restrains the carriage from end-wise movement under the action of the spring so that the treadle may be released, said latch lever having an extension adapted to hold the 5 ruffling blade in engagement with the material when said lug passes off from the face of the carriage, said lug being of sufficient length so that the latch lever may be moved to release the ruffling blade and render it in-
10 effective without releasing the carriage.

In testimony whereof, I affix my signature.
KARL MAIER.
